CLAIM

The ornamental design for a child car seat buckle positioner, as shown and described.

DESCRIPTION

FIG. 1 is a perspective view of a child car seat buckle positioner, showing our new design;

FIG. 2 is a top perspective view thereof;

FIG. 3 is a bottom perspective view thereof;

FIG. 4 is a top plan view thereof;

FIG. 5 is a bottom plan view thereof;

FIG. 6 is a front elevational view thereof, the rear elevational view being a mirror image thereof; and,

FIG. 7 is a left-side elevational view thereof, the right-side elevational view being a mirror image thereof.

The broken line showing a child car seat in FIG. 1 depicts environmental matter that forms no part of the claimed design. The remaining broken lines in the figures depict portions of the child car seat buckle positioner that form no part of the claimed design.

1 Claim, 5 Drawing Sheets
